By his Attorney,

Harold M. Davis

UNITED STATES PATENT OFFICE

KARL SÖHNLE, OF WEISSACH-ON-THE-ENZ, GERMANY, ASSIGNOR, BY MESNE ASSIGNMENTS, TO THE LITTLEWAY PROCESS COMPANY, OF BOSTON, MASSACHUSETTS, A CORPORATION OF MASSACHUSETTS

DEVICE FOR HOLDING SHOE UPPERS IN LASTED POSITION

Application filed March 13, 1931, Serial No. 522,365, and in Germany April 4, 1930.

This invention relates to devices for use in the manufacture of shoes for holding the uppers in lasted position, and more particularly to devices adapted for use temporarily in holding relation to the marginal portion of an upper over an insole on a last to maintain the upper in lasted position until conditions are such that it will remain in that position without the aid of extraneous fastening or holding means, as a result, for example, of the setting of cement applied to fasten the upper to the insole. The invention is herein illustrated by reference to its use in holding the toe-end portion of an upper in lasted position in the manufacture of a shoe of that kind in which the marginal portion of the upper at the toe and elsewhere is lasted over the insole in generally parallel relation to the shoe bottom, but it is to be understood that the invention is not limited in utility to the manufacture of shoes of that particular kind nor to the lasting of the toe ends of shoes.

In lasting the toe ends of shoes with cement there have been used heretofore upper-holding devices which are fastened to the shoes by tacks to maintain them in upper-holding position until the cement has set. The present invention provides a novel upper-holding device having as a part thereof means for securely fastening it to the shoe, thus dispensing with the use of tacks or like fastenings and accordingly effecting a saving of fastenings, the construction being also such as to facilitate and expedite the attachment of the device to the shoe. For the purposes in view the device herein shown comprises a member adapted to be applied in holding relation to the marginal portion of an upper over an insole on a last, and fastening means constituting a part of the device and movable relatively to the upper-holding member to pierce the shoe bottom and thereby to fasten the member in upper-holding position. In the construction shown the fastening means is permanently attached to the upper-holding member, although the invention is not thus limited. More particularly, as illustrated, the upper-holding member has thereon guiding means upon which is movably

mounted a head provided with projections arranged to be forced through the insole into the last by moving the head relatively to the member, a spring being provided to maintain the head normally in a retracted position determined by a stop. The head is so formed as to serve as a handle to assist in positioning the device in proper relation to the shoe and is adapted to be struck with a hammer to force its projections into the shoe. After the cement has set the device may be conveniently detached from the shoe and thereafter may be applied and fastened in the same manner to another shoe.

The novel features of the invention will now be more particularly described by reference to the accompanying drawings and pointed out in the claims.

In the drawings:

Fig. 1 is a perspective view illustrating how the novel upper-holding device is applied to the toe end of a shoe lasted in a bed-lasting machine;

Fig. 2 is a view partly in side elevation and partly in section illustrating more clearly the construction of the device and its relation to the shoe, the toe band of the lasting machine being omitted;

Fig. 3 is a view in side elevation showing the device detached from the shoe; and

Fig. 4 is a perspective view of the toe end of the shoe after removal of the upper-holding device therefrom.

The device herein shown comprises an upper-holding member or plate 10 adapted to be applied in holding relation to the marginal portion of the toe end of an upper extending inwardly over an insole on a last, the plate having an edge contour similar to that of the edge of the toe end of the shoe bottom 90 and being provided along its edge with a plurality of downwardly extending projections or teeth 12 adapted to engage the marginal portion of the upper and to penetrate the upper more or less, forming therein small holes or depressions indicated at 14 in Fig. 4. For fastening the plate 10 in upper-holding position there is permanently associated with it upper-fastening means comprising a block or head 16 slidably mounted on a

guiding pin 18 which is fast on the plate and projects upwardly therefrom, the head 16 having fast thereon a pair of pointed projections or pins 20 arranged to extend through holes 5 22 in the plate and to be forced through the insole and into the last by downward movement of the head 16 after the device has been placed upon the toe end of the shoe bottom. The head 16 is formed to serve as a handle 10 whereby the device may be conveniently positioned by the operator in proper relation to the shoe, and it may be struck by a hammer to force the projections 20 into the shoe, as illustrated in Fig. 2, or may be forced downward- 15 ly in any other convenient manner. Within the head 16 there is provided a spring 24 which bears on the upper end of the pin 18 and serves normally to maintain the head in a retracted position, as illustrated in Fig. 3, 20 the retractive movement of the head being limited by a small pin 26 which projects from the pin 18 into slots in opposite sides of the head.

It will be understood that before the above- 25 described upper-holding device is applied to the shoe the toe end of the upper will be conformed to the contour of the last, for example by the use of the wipers 28 (Fig. 1) of a bed-lasting machine, the upper being 30 clamped about the toe by a toe band 30 as the wipers wipe its marginal portion inwardly over the insole. The marginal portion of the upper may thus be wiped inwardly over the insole before cement is applied, and again 35 after the application of cement, whereupon the wipers will be somewhat retracted and the upper-holding device will be placed upon the upper with the teeth 12 nearest the end of the toe in contact with the edges of the wipers.

40 The wipers may then be advanced and closed to force the device somewhat rearwardly over the shoe bottom and thus to draw the upper more tightly inward from the edge of the shoe bottom at the end of the toe, the wipers 45 also serving to locate the device in proper position widthwise of the shoe if it is not already in that position. After this the head 16 will be moved downwardly by striking it with a hammer, or in some other manner, thus 50 forcing the projections 20 through the insole and into the last to fasten the device to the shoe. The plate 10 will thus be clamped down upon the shoe bottom through the spring 24 and preferably also by positive engagement of the lower end of the head 16 with the plate, as illustrated in Fig. 2. The teeth 12, which may penetrate more or less 55 through the upper materials, will then hold the toe end of the upper effectively in lasted position until the cement has set. It will be understood that the shoe will be removed from the lasting machine with the upper-holding device fastened thereon. After the cement has set the device will be detached 60 from the shoe by force applied to the head 16

or by inserting a suitable tool under the plate 10 and prying the device away from the shoe bottom.

It will be observed that the head 16 is positioned substantially midway between the opposite sides of the plate 10 on a portion of the plate which extends farther inwardly over the shoe bottom than its upper-engaging portion and is arranged in spaced relation to the shoe bottom, and that the projections 20 are arranged to pierce the insole and last in locations farther inwardly from the edge of the shoe bottom than the marginal portion of the upper where there is less danger of damaging the last than if the projections were arranged near the edge of the shoe bottom and where also there is no danger of disturbing the margin of the upper in removing the device from the shoe. While the drawings show two projections 20 located substantially midway between the sides of the toe, it will be understood that the invention is not limited to this particular arrangement nor to this particular number of projections. It is further to be understood that the invention is not limited to a device having teeth such as 12 for engaging the upper.

While the invention is herein described with reference to its use on a shoe in which the toe end of the upper is fastened to the insole by cement, it is not thus limited in its applicability, but is useful, for example, in lasting toes including in the marginal portion of the upper box toe stiffening material which may act of itself, after hardening, to maintain the toe portion of the upper in lasted position. It will also be evident that the device illustrated may be used, if desired, in lasting the heel ends of shoes.

Having described the invention, what I claim as new and desire to secure by Letters Patent of the United States is:

1. A device for holding shoe uppers in lasted position, comprising a member adapted to be applied in holding relation to the marginal portion of an upper over an insole on a last, and fastening means constituting a part of the device and movable relatively to said upper-holding member to pierce the insole and thereby to fasten the member in upper-holding position.

2. A device for holding shoe uppers in lasted position, comprising a member adapted to be applied in holding relation to the marginal portion of an upper over an insole on a last, and fastening means comprising a plurality of pointed pins constituting a part of the device and movable as a unit relatively to the upper-holding member to pierce the insole and last and thereby to fasten the member in upper-holding position.

3. A device for holding shoe uppers in lasted position, comprising a member adapted to be applied in holding relation to the marginal portion of an upper over an insole on a last,

and fastening means permanently attached to said upper-holding member and movable relatively to the member to pierce the insole and thereby to fasten the member in upper-holding position.

4. A device for holding shoe uppers in lasted position, comprising a member adapted to be applied in holding relation to the marginal portion of an upper over an insole on a last, and a block movable relatively to said upper-holding member and provided with a plurality of projections arranged to pierce the insole to fasten the member in upper-holding position.

10 5. A device for holding shoe uppers in lasted position, comprising a member adapted to be applied in holding relation to the marginal portion of an upper over an insole on a last, and a head permanently attached to said upper-holding member and movable relatively to the member toward the bottom of the last, said head being provided with one or more projections arranged to be forced through the insole into the last to fasten the member in upper-holding position.

20 6. A device for holding shoe uppers in lasted position, comprising a member adapted to be applied in holding relation to the marginal portion of an upper over an insole on a last, said member having guiding means thereon, and a head slidably mounted on said guiding means for movements toward and from the bottom of the last and provided with one or more projections arranged to be forced through the insole into the last to fasten the device to the shoe.

30 7. A device for holding shoe uppers in lasted position, comprising a member adapted to be applied in holding relation to the marginal portion of an upper over an insole on a last, fastening means movable relatively to said upper-holding member to pierce the insole and thereby to fasten the member in upper-holding position, and spring means arranged 40 to maintain said fastening means normally in a retracted position.

45 8. A device for holding shoe uppers in lasted position, comprising a member adapted to be applied in holding relation to the marginal portion of an upper over an insole on a last, a head movable relatively to said upper-holding member toward and from the bottom of the last and provided with one or more projections arranged to pierce the insole to fasten the device to the shoe, and spring means 50 for normally maintaining said head in a retracted position.

55 9. A device for holding shoe uppers in lasted position, comprising a member adapted to be applied in holding relation to the marginal portion of an upper over an insole on a last, said member having a guide projecting upwardly therefrom, a head mounted on said guide for movements toward and from the bottom of the last and provided with a plu-

rality of projections arranged to pierce the insole to fasten the device to the shoe, and a spring arranged to maintain said head normally in a retracted position.

10 10. A device for holding shoe uppers in lasted position comprising a member adapted to be applied in holding relation to the marginal portion of an upper over an insole on a last, and a head movably supported on said upper-holding member and formed to serve as a handle for placing the member on the shoe, said head having one or more projections thereon arranged to be moved relatively to the upper-holding member to pierce the shoe bottom and thereby to fasten the member in upper-holding position.

15 11. A device for holding shoe uppers in lasted position, comprising a member adapted to be applied in holding relation to the marginal portion of an upper over an insole on a last, said member having guiding means thereon, and a head movable on said guiding means toward the shoe bottom and adapted to be struck with a hammer, said head having one or more projections thereon arranged to pierce the shoe bottom to fasten the member in upper-holding position.

20 12. A device for holding shoe uppers in lasted position, comprising a member adapted to be applied in holding relation to the marginal portion of an upper over an insole on a last, and a block movable relatively to said member to clamp the member down on the shoe bottom, said block having one or more pointed pins thereon arranged to pierce the shoe bottom to fasten the block in clamping position.

25 13. A device for holding shoe uppers in lasted position, comprising a member adapted to be applied in holding relation to the marginal portion of an upper over an insole on a last, fastening means supported on said upper-holding member to move relatively to the member in directions toward and from the shoe bottom and formed to pierce the shoe bottom to fasten the member in upper-holding position, and means for limiting movement of the fastening means in a direction away from the shoe bottom.

30 14. A device for holding shoe uppers in lasted position, comprising a member adapted to be applied in holding relation to the marginal portion of an upper over an insole on a last, fastening means supported on said upper-holding member to move relatively to the member in directions toward and from the shoe bottom and formed to pierce the shoe bottom to fasten the member in upper-holding position, a spring for maintaining the fastening means normally in a retracted position, and a stop for limiting retractive movement of the fastening means under the influence of said spring.

35 15. A device for holding shoe uppers in lasted position, comprising a member adapt-

- ed to be applied in holding relation to the marginal portion of an upper overlying an insole around an end of the bottom of a last, and fastening means movably supported on said upper holding member in a location substantially midway between the opposite sides of the member and having one or more projections arranged to pierce the shoe bottom to fasten the member in upper-holding position.
16. A device for holding shoe uppers in lasted position, comprising a member adapted to be applied in holding relation to the marginal portion of an upper overlying an insole around an end of the bottom of a last, and fastening means comprising a plurality of projections movable as a unit relatively to said upper-holding member to pierce the shoe bottom in locations farther inwardly from the edge of the insole than the margin of the upper to fasten the member in upper-holding position.
17. A device for holding shoe uppers in lasted position, comprising a member adapted to be applied in holding relation to the marginal portion of an upper overlying an insole around an end of the bottom of a last, and fastening means permanently attached to said upper-holding member and movable relatively to the member in directions toward and from the shoe bottom, said fastening means having one or more projections arranged to pierce the insole farther inwardly from the edge of the shoe bottom than the margin of the upper to fasten the member in upper-holding position.
18. A device for holding shoe uppers in lasted position, comprising a plate having an edge contour similar to that of the edge of an end of an insole and having a plurality of teeth along its edge arranged for holding engagement with the marginal portion of an upper overlying the insole, and fastening means comprising a plurality of projections movable as a unit relatively to the plate to pierce the shoe bottom and thereby to fasten the plate in upper-holding position.
19. A device for holding shoe uppers in lasted position, comprising a plate having an edge contour similar to that of the edge of an end of an insole and having a plurality of teeth along its edge arranged for holding engagement with the marginal portion of an upper overlying the insole, and a member supported on said plate for reciprocatory movements and having one or more projections arranged to pierce the shoe bottom to fasten the plate in upper-holding position.
20. A device for holding shoe uppers in lasted position, comprising a member adapted to be applied in holding relation to the marginal portion of an upper overlying an insole around an end of the bottom of a last, said member having a portion extending farther inwardly over the shoe bottom than its upper-holding portion and arranged in spaced relation to the shoe bottom, and fastening means mounted upon said inwardly extending portion of the member and movable relatively to the member to pierce the shoe bottom and thereby to fasten the member in upper-holding position.
21. A device for holding shoe uppers in lasted position, comprising a member adapted to be applied in holding relation to the marginal portion of an upper overlying an insole around an end of the bottom of a last, said member having a portion extending farther inwardly over the shoe bottom than its upper-holding portion and arranged in spaced relation to the shoe bottom, and fastening means comprising a plurality of pointed pins movable relatively to the member to pierce the shoe bottom and arranged to cooperate with said inwardly extending portion of the member to fasten the member in upper-holding position.
22. A device for holding shoe uppers in lasted position, comprising a member adapted to be applied in holding relation to the marginal portion of an upper overlying an insole around an end of the bottom of a last, said member having a portion extending farther inwardly over the shoe bottom than its upper-holding portion and arranged in spaced relation to the shoe bottom, and a head supported on said inwardly extending portion of the member to move relatively to the member heightwise of the shoe and having one or more projections arranged to pierce the shoe bottom to fasten the device to the shoe.
23. A device for holding the toe ends of shoe uppers in lasted position, comprising an upper-holding plate adapted to be placed on a shoe over the toe end of the shoe bottom, and a block movable relatively to said plate and having thereon a plurality of projections arranged to pierce the shoe bottom to fasten the device to the shoe.
24. A device for holding the toe ends of shoe uppers in lasted position, comprising an upper-holding plate adapted to be placed on a shoe over the toe end of the shoe bottom, a guide projecting from said plate, and a member movably mounted on said guide and provided with means formed to pierce the shoe bottom to fasten the device to the shoe.
25. A device for holding the toe ends of shoe uppers in lasted position, comprising an upper-holding plate adapted to be placed on a shoe over the toe end of the shoe bottom, a member movably supported on said plate and provided with means formed to pierce the shoe bottom, and a spring against the resistance of which said member is movable toward the shoe bottom.
- In testimony whereof I have signed my name to this specification.
